SPRING BED BOTTOM

Reinhold W. Marquardt, Milwaukee, Wis.

Application November 18, 1935, Serial No. 50,350

3 Claims. (Cl. 5—248)

This invention relates to improvements in spring bed bottoms. The present invention is a companion to application Serial Number 765,248, filed December 6, 1934.

As in the above identified companion application, it is broadly the object of the present invention to minimize recoil and to increase the resilience in a spring bed bottom by the provision of a fully floating base upon which the coil springs are carried. The present invention seeks to accomplish this broad result in a different and improved manner in which side sway is inherently opposed and increased stability provided by the character of the springs which support the floating subframe from the main frame.

In the drawing:

Figure 1 is a plan view of a bed bottom embodying the present invention, only a view of the supporting helical springs and only a portion of the connecting structure being illustrated in full.

Figure 2 is an enlarged detail view taken in section transversely through a fragment of the main frame, subframe and top frame.

Like parts are designated by the same reference characters throughout the several views.

The spring bed bottom of the present invention preferably comprises four separate frames. There is a main frame at 3 arranged to rest upon the rails of the bed. Slightly above and within this is the floating subframe 4 and at the top of the bed bottom in substantial registration with the main frame is the top marginal frame 5. Between the frames 3 and 5, I may use a floating intermediate frame 2. All of the several frames are of generally rectangular form with rounded corners.

The strap iron supports 6 for the coil springs 7 are anchored to the floating subframe 4. The coil springs 8 around the outside of the bed bottom are similar to coil springs 7 except that they are slightly shorter by reason of the fact that they rest directly on the floating subframe 4. The tops of coil springs 8 are connected directly with the top marginal frame 5 while the tops of coil springs 7 and 8 are interconnected by a special fabric hereinafter to be described to provide support for a mattress. The intermediate frame 2 serves as a terminus for connecting wires 9 and 10 which are laced through the intermediate portions of helicals 7 and 8 to support such helicals against lateral collapse. This is not essential but it is preferred where the helicals have the elongated and highly elastic character indicated.

The means for carrying the floating frame 4 from the main frame 3 may conveniently comprise brackets mounted on the respective frames and short helical springs interposed under compression between the two brackets. The bracket 11 is an angle bracket riveted to the inside of the main frame 3. The bracket 12 comprises simply a small plate riveted to the under surface of the top flange of the subframe 4. Between the brackets 11 and 12 is seated the flat ended compression spring 15 centered on the guide disks 16 and 17 respectively, and confined against undue expansion by means of the adjustable tension bolt 18. The bolt also serves as a guide tended to prevent lateral movement between the brackets 11 and 12 in the course of compression of spring 15. As clearly indicated in Figure 1, there is a series of the brackets and supporting helical springs along each side of the bed bottom assembly. This structure may also be duplicated at the ends, but I prefer to use at the ends short tension coil springs 19 directly connecting the subframe 4 with the main frame 3.

To provide a relatively closely woven mattress fabric at the top of the structure, I prefer to use rows of flexible metal straps 20 and 21 interposed in both directions between the rows of supporting helicals. Where the straps 20 and 21 cross, I provide disks 22 having shallow channels to accommodate the uppermost straps 21 and held in place by rivets 23 which pass through the disk and both straps. Short coil springs 24 under tension connect the respective disks with the top coils of all of the adjacent helicals. The rivets positively prevent any displacement and consequent rubbing of the straps 20 and 21 with respect to each other, thus eliminating one source of noise.

I have found that a bed bottom embodying this invention is unusually stable and unusually soft. Not only does the resilience of compression springs 15 supplement that of the coil springs 8, but the flat ended form of the compression springs 15, supplemented by the guide of bolts 18, tends to prevent and eliminate side sway. Thus the device is exceptionally resilient in a vertical direction and is very much less yieldable laterally.

I claim:

1. A spring structure comprising the combination with a portable main frame comprising angle iron sides having horizontal flanges and vertical flanges along the inner margins of the horizontal flanges, of a floating sub-frame having angle iron side rails with their flanges correspondingly dis-

- posed, the horizontal flange of each sub-frame rail being within and only slightly above the horizontal flange of the main frame rails, bracket members projecting laterally from the horizontal flange of the sub-frame rails, angle bracket members projecting inwardly from the main frame rails to positions directly beneath the bracket members first mentioned, limiting means connecting the respective bracket members, and compression springs interposed between respective bracket members for the support of the sub-frame from the main frame, together with a floating top frame substantially directly above the main frame, coil springs connected with the top frame and with each other to comprise a bed bottom fabric, and means including said sub-frame for the support of said coil springs.
2. In a spring structure, the combination with a portable main frame, of a floating sub-frame within and only slightly above the main frame, a bed bottom comprising supporting springs mounted on said sub-frame independently of the main frame, bracket members spaced along opposite side portions of the main frame and projecting inwardly therefrom, complementary bracket members spaced at like intervals along the sides of the sub-frame and projecting out-

wardly therefrom into superposed relation to the bracket members of the main frame, limiting means connecting the superposed portions of the respective bracket members, and compression springs surrounding the respective limiting means and confined between the superposed portions of the respective bracket members and between the respective frames for the support of the sub-frame from the main frame.

3. A spring structure comprising the combination with a main frame having four sides and a floating subframe having corresponding sides spaced within the respective sides of the main frame and at almost the same level, bracket members connected with the respective frames and projecting laterally in opposite directions from the corresponding sides thereof, the bracket members connected with the respective frames having vertically spaced superposed portions, and substantially flat ended compression springs interposed between the said portions of the respective bracket members and laterally disposed between the corresponding sides of the respective frames for the support of the subframe from the main frame.
